BINDER

Henry T. Adams, Chicago, Ill.

Application February 29, 1940, Serial No. 321,559

2 Claims. (Cl. 129—1)

This invention relates to a binder which may be attached to covers or other surfaces for releasably securing perforated sheets thereto.

An object of the present invention is to provide extremely simple parts by which sheets may be secured to a cover, book or other surfaces. A further object is to provide a binder equipped with a large number of prongs equipped to receive a large number of sheets, the sheets being readily removed as desired and new sheets inserted. A further object is to provide a mechanism of extremely simple and inexpensive structure by which sheets may be firmly supported within a book or other object but released therefrom for the removal or the insertion of sheets, the mechanism consisting of two simple parts equipped with integral interlocking members. Other specific objects and advantages will appear as the specification proceeds.

The invention is illustrated in a preferred embodiment, by the accompanying drawing, in which—

Figure 1 is a broken plan view of a cover equipped with a binder embodying my invention; Fig. 2, an enlarged transverse sectional view, the section being taken as indicated at line 2 of Fig. 1; Fig. 3, an enlarged plan view of the binder parts shown with the paper sheets removed but with the parts shown in interlocking engagement; Fig. 4, a view similar to Fig. 3 but with the parts in unlocked position; and Fig. 5, a broken plan view of the metal back strip employed.

In the illustration given, A designates a cover; B, a metal back secured to the cover; and C, a sheet engaging member.

The cover A may be of any suitable structure. It does not per se form a part of the present invention. The binder, which comprises parts B and C may be secured to any suitable book, cover or any other surface to which the sheets are to be attached. Further, if desired, the binder parts B and C need not be secured to any surfaces but may be employed separately for securing or binding together a number of perforated sheets.

The metal back strip B consists of a single strip of sheet metal having one end thereof curved upwardly slightly as indicated by the numeral 10. The strip is secured by rivets or other fasteners to the cover A. Along one side, the back strip B is provided with upwardly and inwardly facing tongues 11. On the other side and adjacent the curved surface 10 are tongues 12 which face toward tongues 11 but which are

spaced intermediate an opposite pair of tongues 11.

The prong carrying member or sheet engaging member C preferably comprises a retaining flange portion 13 having a central channel 14 for reinforcing the same and also for providing a space for the fastener therebelow. The retaining flange is provided with a rear edge portion 15 adapted to engage the tongues 11. From the front portion of the flange 14 extend a plurality of spaced prongs 16 curved in the form illustrated in Fig. 2. Between the prongs 16 extend arcuate locking flanges 17. When the member C is in interlocking engagement with the metal back strip B, the flanges 17 are in engagement with the tongues 12, as shown more clearly in Fig. 3. When the member C is released from locking position, the locking flanges 17 extend to one side of the tongues 12, as shown more clearly in Fig. 4.

In the particular illustration given, the member C is provided at its ends with short vertical flanges 18 which assist in the lateral movement of the member C to locking and unlocking positions. The flanges may, however, be omitted.

When the member C is released from engagement with the back strip B, it may be lifted free thereof and the prongs 16 provide between them and the flanges 17 an open space through which the perforated leaves 19 may be passed, the prongs 16 being passed through the perforations of the leaves.

Operation

In the operation of the device, the prong carrying member C, which is released from engagement with the metal back B is supported so that a group of perforated sheets may be inserted upon the free ends of the prongs with the prongs extending through the perforations, as illustrated in Fig. 2. The member C is then placed upon the back plate B with the flange 15 engaging the tongues 11 and with the locking flanges 17 disposed between the tongues 12, as illustrated in Fig. 4. The member C is then moved laterally of the cover A so as to bring the flanges 17 under the tongues 12, thus locking the member C securely to the backing B, as illustrated in Figs. 2 and 3. It will be noted that the forward curved edge 10 of the back plate B closes the lower ends of the prongs 16 and protects the same. Outward movement or tension upon the prongs 16 causes them to engage the curved plate portion 10 whereby they are maintained in confining position.

When it is desired to remove sheets or to insert new sheets, the member C is pressed laterally

so as to bring the flanges 17 back to the position illustrated in Fig. 4. The member B may then be tilted upwardly and forwardly to bring the edge 15 out of engagement with tongues 11, thus freeing the member C. After the substitution, removal or insertion of sheets has been completed, the member C may be replaced and again locked into position in the manner already described.

It will be understood that the prongs 16 may have their ends extend outside of the curved flange 10 if desired. Also, the tongues may be reversed with respect to the different parts so as to provide the same interlocking effect.

While in the foregoing specification, I have set forth, for the purpose of illustration, certain specific details or structure, it will be understood that such structure may be modified and the working parts thereof reversed to a substantial

extent, without departing from the spirit of my invention.

I claim:

1. In a binder, a metal back strip provided with spaced rows of locking tongues, a prong carrying member equipped with flanges adapted to engage said rows of tongues, prongs carried by said member and having their free ends terminating adjacent an edge of said back strip, said last-mentioned edge of said back strip being curved so as to lie adjacent the free ends of said prongs.

2. In a binder, a back strip equipped with spaced rows of locking tongues and with an arcuate edge, a prong member equipped with flanges releasably engaging said tongues, and arcuate prongs carried by said prong member and having free ends terminating inside and adjacent the arcuate edge of said back strip.

HENRY T. ADAMS.
